UNITED STATES PATENT OFFICE.

WILLIAM H. RIECHERS, OF HAMMOND, INDIANA.

WIRE-COATING APPARATUS.

1,333,132.

Specification of Letters Patent.

Patented Mar. 9, 1920.

Application filed April 19, 1919. Serial No. 291,226.

To all whom it may concern:

Be it known that I, WILLIAM H. RIECHERS, a citizen of the United States, residing at Hammond, in the county of Lake and State 5 of Indiana, have invented new and useful Improvements in Wire-Coating Apparatus, of which the following is a specification.

This invention relates to apparatus for applying a coating of paint or other liquid 10 preserving material to fence wires to protect the same from the deleterious effects of exposure to the elements, and more particularly an apparatus of this kind which operates on the wires without removing them 15 from their supports. The apparatus operates by being carried along a wire, the paint or other protective coating material being automatically applied.

The invention has for its object to provide 20 a simple, efficient and easily controlled apparatus of the kind stated, and to this end it consists in a novel combination and arrangement of parts to be hereinafter described and claimed.

In order that the invention may be better 25 understood, reference is had to the accompanying drawing forming a part of this specification, and in said drawing,

Figure 1 is a plan view of the invention, 30 and

Fig. 2 is a rear elevation thereof, with parts broken away in both views.

Referring specifically to the drawing, the body of the apparatus is in the form of a 35 rectangular receptacle 5 of a size to hold a suitable quantity of paint or other liquid coating material shown at 6 in Fig. 2. The front and rear walls 7 and 7^a of the receptacle are reinforced by straps 8 and 9, and the latter carries a handle 10 for the left hand of 40 the operator. The top of the receptacle has a door 11 hinged at 12, and making a tight fit with the receptacle top edge to prevent the liquid from splashing out.

The front wall 7 of the receptacle carries 45 a bracket 13 which supports a guide roller 14 for the device, adapted to ride on the wire W to be coated. The bracket 13 is twisted to form a base 15 which is riveted or otherwise 50 secured to the strap 8 and the wall of the receptacle. In the front and rear walls of the receptacle are alined apertures 16 through which the wire W passes. These apertures are so located that the wire passes 55 across the inside of the receptacle above the level of the liquid 6 therein.

The front wall 7 also supports bearing brackets 18 for a shaft 19 having an operating handle 20. On this shaft are bevel gears 21 which are in mesh with bevel gears 60 22 on parallel and laterally spaced shafts 23 and 23^a extending horizontally across the interior of the receptacle between the front and rear walls thereof, and supported by said walls and the straps 8 and 9. Each 65 shaft carries a polygonal block 24 on the faces of which are mounted the backs 25 of long-bristled wire brushes 26. The block may be hexagonal as shown or in any other polygonal shape. These brushes are shown 70 set obliquely on the blocks, but any other arrangement may be followed and the two brush units are located to operate on opposite sides of the wire W where it passes through the receptacle. The brush units 75 have their axes parallel to the wire and they are rotated in opposite directions when the handle 20 is operated. By the oblique setting of the brushes a wiping action longitudinally of the wire is obtained. 80

Back of the brush unit of the shaft 23 is another brush unit 27 carried by a sleeve 28 loosely mounted on said shaft and obtaining motion through a sprocket-and-chain or other suitable driving means 29 from the 85 shaft 23^a. The brush unit 27 therefore rotates in the same direction as the brush unit of the shaft 23^a. This extra brush unit 27 is designed to coat the wire W from underneath to assure a complete coating of the 90 same at the bottom as well as the top and the sides.

The brush units are positioned to dip into the liquid 6 as they rotate, and as the wire W passes along between said units the 95 brushes apply the coating thereto. In operation, the apparatus is supported on the wire by the roller 14 and by the operator grasping the handle 10 with one hand, leaving the other hand free to operate the handle 100 20, and it is fed along the wire by simply pushing it along the same. To mount the apparatus on the wire, the door 11 must first be swung open, after which it can be placed to bring the wire through the apertures 16, 105 105 the latter being partly in the top edge of the receptacle and the bottom edge of the cover.

The top of the receptacle carries two baffle plates 30 positioned in the path of the brush units to flex the bristles as they wipe across 110 said plates, and when the bristles clear the plates they are suddenly released and

straighten out, whereupon the coating liquid is thrown down or splashed on the wire with force, making the coating of the latter thorough. The brush units, of course, are positioned to dip into the liquid 6 as shown in Fig. 2.

I claim:

1. An apparatus for coating wire strands, comprising a receptacle for holding a supply of liquid coating and having aligned apertures in opposite sides for the passage across the interior of the receptacle of the wire to be coated, a supporting roller adjacent to one of the apertures and engageable by the wire, a handle on the receptacle on the side thereof having the other aperture, rotary brushes in the receptacle having their axes parallel to the wire and they positioned to operate on opposite sides of the wire, and actuating means for the brushes.
2. An apparatus for coating wire strands comprising a receptacle across the interior of which the wire is adapted to pass, rotary brushes in the receptacle having their axes parallel to the wire and they positioned to operate on opposite sides of the wire, and actuating means for the brushes.
3. An apparatus for coating wire strands comprising a receptacle across the interior of which the wire is adapted to pass, rotary brushes in the receptacle having their axes parallel to the wire and they positioned to operate on opposite sides of the wire, actuating means for the brushes, and baffle plates in the receptacle positioned in the path of the brush bristles to flex the same and splash the coating liquid on the wire when the bristles clear said plates.
4. An apparatus for coating wire strands comprising a receptacle across the interior of which the wire is adapted to pass, rotary brushes in the receptacle positioned to operate on opposite sides of the wire, shafts carrying the brushes, gears on the shafts, a shaft geared to said gears, and actuating means for the last-mentioned shaft on the outside of the receptacle.
5. An apparatus for coating wire strands comprising a receptacle across the interior of which the wire is adapted to pass, rotary

brushes in the receptacle positioned to operate on opposite sides of the wire, shafts carrying the brushes, and means for rotating the shafts in opposite directions.

55

6. An apparatus for coating wire strands comprising a receptacle across the interior of which the wire is adapted to pass, rotary brushes in the receptacle positioned to operate on opposite sides of the wire, shafts carrying the brushes, bevel gears on the shaft, and an operating shaft having bevel gears in mesh with the first-mentioned bevel gears for rotating their shafts in opposite directions.

65

7. An apparatus for coating wire strands comprising a receptacle across the interior of which the wire is adapted to pass, rotary brushes in the receptacle positioned to operate on opposite sides of the wire, and turning in opposite directions, and actuating means for the brushes.

70

8. An apparatus for coating wire strands comprising a receptacle across the interior of which the wire is adapted to pass, rotary brushes in the receptacle positioned to operate on opposite sides of the wire, shafts carrying the brushes, means for rotating the shafts in opposite directions, and another brush supported by one of the shafts and 80 rotating in the same direction as the brush of other shaft.

75

9. An apparatus for coating wire strands comprising a receptacle across the interior of which the wire is adapted to pass, rotary brushes in the receptacle positioned to operate on opposite sides of the wire, shafts carrying the brushes, means for rotating the shafts in opposite directions, and another brush supported by one of the shafts and 90 rotating in the same direction as the brush of other shaft, and obtaining motion from the latter shaft.

85

10. An apparatus for coating wire strands comprising a receptacle across the interior 95 of which the wire is adapted to pass, rotary brushes in the receptacle positioned to operate on opposite sides of the wire, and set obliquely with respect to their axes, and actuating means for the brushes.

100

In testimony whereof I affix my signature.
WILLIAM H. RIECHERS.
